Primary Examiner — L. Martinez(74) *Attorney, Agent, or Firm* — Borden Ladner Gervais LLP; Curtis B. Behmann**CLAIM**

The ornamental design for a door jamb extrusion, as shown and described.

DESCRIPTION

FIG. 1 is a perspective view of a door jamb extrusion showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom view thereof.

The door jamb extrusion is shown with a symbolic break in its length. The appearance of any portion of the door jamb extrusion between the jagged break lines forms no part of the claimed design.
